A. M. AUFTRING.
STEAM PRESSURE STERILIZER VALVE.
APPLICATION FILED AUG. 21, 1915.

1,183,943.

Patented May 23, 1916.

UNITED STATES PATENT OFFICE.

ALBERT M. AUFTRING, OF HAMMOND, INDIANA, ASSIGNOR TO FRANK S. BETZ, OF HAMMOND, INDIANA.

STEAM-PRESSURE-STERILIZER VALVE.

1,183,943.

Specification of Letters Patent. Patented May 23, 1916.

Application filed August 21, 1915. Serial No. 46,745.

To all whom it may concern:

Be it known that I, ALBERT M. AUFTRING, a citizen of the United States of America, and a resident of Hammond, county of Lake, 5 State of Indiana, have invented certain new and useful Improvements in Steam-Pressure-Sterilizer Valves, of which the following is a specification.

The main objects of this invention are to 10 provide an improved form of valve for use on sterilizing apparatus designed to insure and facilitate proper operation of the apparatus; to provide an improved arrangement of passage in said valve whereby a 15 greater diversity of operation is permitted and controlled by a single valve; and to provide a valve of this kind which is compact in construction and simple in operation.

An illustrative embodiment of this invention is shown in the accompanying drawings, in which:

Figure 1 is a front elevation of the improved valve, the dotted outlines representing the steam generating and sterilizing 25 compartments. Fig. 2 is an enlarged longitudinal sectional elevation of the valve taken on the line A—A of Fig. 1. Fig. 3 is an enlarged fragmentary sectional plan of the valve taken on the line B—B of Fig. 1 showing 30 the arrangement of the passages when the valve is set for connecting the steam generator with the sterilizing chamber. Fig. 4 is a transverse section of the same taken on the line C—C of Fig. 2. Fig. 5 is a view 35 similar to Fig. 3 but showing the position of the valve for closing all communication through the different passages. Fig. 6 is another view similar to Fig. 3, but showing the position of the valve for permitting 40 communication between the sterilizing chamber and the discharge passage of the valve. Fig. 7 is a similar view showing the position of the valve when set for creating a vacuum in the sterilizing chamber.

In the construction shown in the drawings, the valve comprises a casing 1 and member or plug 2, the latter of which is of the usual tapered construction, and is rotatably held in a socket 3 by means of a nut 4. 45 The nut 4 is threaded onto the casing 1 and has an annular flange 4.1 engaging an an-

nular shoulder 5 on said member which secures the member against displacement. A hand wheel 6 or other operating device is secured to the member 5 for the purpose of 55 rotating the same.

The casing 1 is adapted to be placed upon the front rim of a sterilizer and to have pipes 7 and 8 connected thereto leading respectively to the steam generator chamber 9, 60 represented by the space between the dotted circles A and B (Fig. 1), and a sterilizing chamber 10, represented by the space within the dotted circle B.

A plurality of passages are formed in the 65 casing 1 and member 2, so that for different angular positions of said member they will connect either the steam generating chamber 9 with the sterilizing chamber 10, or the sterilizing chamber 10 with the discharge, or connect the steam generator 9 and the sterilizing chamber 10 with an 70 ejector for the purpose of exhausting the sterilizer chamber to create a vacuum there- 75 in. These passages comprise radially dis- posed passages 11 and 12 formed in the cas- ing 1, and connecting with the pipes 7 and 8 respectively through the medium of cham- bers 13 and 14 and passages 15 and 16.

A radially disposed passage 17 is formed 80 in the member 2 so as to coact with the pas- sages 11 and 12 in controlling communica- 85 tion between the steam generator and the sterilizing chamber. Branch passages 18 and 19 are formed in the casing 1, connect- 90 ing with the chambers 13 and 14 by means of which they communicate directly with the by-passages 15 and 16. These branch pas- 95 sages are arranged so as to coact with dia- gonal passages 20, 21, and 22 formed in the member 2 to permit the chambers 9 and 10 to be connected in various ways with the axially disposed discharge passage 23. The passage 20 connects with an axially disposed 100 passage 24 formed in the end of the mem- ber 2, which in turn communicates with a passage 25 formed in the nozzle 26 secured to the end of the member 2 in alinement with the discharge passage 23. The passages 21 and 22 are formed so as to open into the chamber 27 formed between the end of the member 2 and the casing 1. The angularity

of the passages 20, 21, and 22 is arranged so that the passage 21 will register with the branch casing passage 19 for a certain position of said member, and the passages 5 20 and 22 will register simultaneously with the branch casing passages 18 and 19 respectively for another position of the member 2. The discharge passage 23 is formed in a nipple 28 which is screwed into the end 10 of the casing 1 and locked by means of a nut 29, so that the end of the nozzle 26 projects slightly into the inner end of the passage 23, thereby forming an ejector construction. The outer end of the passage 23 15 diverges somewhat in the form of a nozzle.

A pointer 30 is secured to the member 2 so as to coat with markings on a dial 31 secured to the casing 1 for indicating the various positions of the valve. As shown 20 in Fig. 1 there are four positions, the markings therefor being respectively "Steril", "Closed", "Exh" and "Vacuum". Pins or shoulders 32 are formed on the dial 31, in position to be engaged by the 25 pin 30 for limiting the throw of the member 2. When the valve is turned so that the pointer registers with the first of the above mentioned markings "Steril", the passage 17 in the member 2 is brought into 30 alinement with the casing passages 11 and 12, thereby connecting the steam generator 9 with the sterilizing chamber 10, so as to admit steam into said chamber to effect the sterilizing operation in the well-known 35 manner. The relative location of the passages for this position of the valve is shown in Figs. 3 and 4. When the valve is turned so that the pointer registers with the second of the above markings "Closed", all passages 40 in the member 2 and casing 1 are shifted out of registration as indicated in Fig. 5. When the valve is shifted to bring the pointer 30 into registration with the marking "Exh" the diagonal passage 22 in the 45 member 1 registers with branch passage 19, so that through the medium of the chamber 14 and passage 16 the sterilizing chamber 10 communicates directly with the discharge passage 23, and permits the steam previously injected into the chamber to 50 exhaust through said discharge passage. When the valve has been shifted so that the pointer 30 registers with the last of the 55 above named dial markings, the diagonal passages 20 and 21 are brought simultaneously into registration respectively with the branch passages 18 and 19, as is represented in Fig. 7. This position of the valve permits the steam from the generator 9 to 60 be discharged through the nozzle 26 into the discharge passage 23, which in a well-known manner causes air to be drawn from the chamber 3 along with the jet of steam, and through the medium of the passages 21, 65 19 and 16 creates a suction on the steriliz-

ing chamber 10, so as to produce a partial vacuum therein.

This arrangement of the valve provides a very compact device which is extremely simple in its operation, and so arranged 70 that there is little, if any, danger of faulty operation of the sterilizer.

Although but one specific embodiment of this invention has been herein shown and described, it will be understood that numerous details of the construction shown may be altered or omitted without departing 75 from the spirit of this invention as defined by the following claims.

I claim:

1. A valve, comprising: a casing; and a rotatable member fitting therein, said casing having a discharge passage and two other passages, one of which is arranged for connection with a source of supply; and the 80 other with a receptacle, said member having a plurality of angularly disposed passages arranged to so connect with the passages in said casing as to provide communication between said receptacle and either said source of supply or said discharge passage, and provide communication simultaneously by non-connecting channels between said discharge passage and said source of supply and said receptacle. 85

2. A valve, comprising: a casing and a rotatable member fitting therein, said casing having diametrically opposed passages, arranged radially with respect to the axis of rotation of said member, and an axially disposed discharge passage, one of said radial casing passages being arranged for connection to a source of supply; and the other for connection with a receptacle, said plug having a radially disposed passage 90 adapted to connect said radial casing passages, and having other diagonally disposed passages adapted to connect with said discharge passages either both of said radial casing passages simultaneously by non-connecting channels or one of said radial casing 95 passages independently of the other. 100

3. A valve, comprising: a casing; and a rotatable member fitting therein, said casing having an axially disposed discharge passage and two radially disposed passages arranged for connection with a source of supply and a receptacle respectively, said member having a radially disposed passage 115 adapted to connect the radially disposed casing passages and having an axially disposed passage extending inwardly from the end, a nozzle secured to the end of the said member and having a passage extending therethrough and forming a continuation 120 of the axially disposed passage in said member, said nozzle being arranged with respect to said discharge passage to form an ejector, said member also having a plurality of diagonally disposed passages, one 125

arranged to connect said axial passage with one of said radial casing passages, and two others arranged to separately connect the other radial casing passage with said discharge passage forwardly of the end of said nozzle, one of said other two diagonal passages being arranged to register with

said other radial casing passage simultaneously with the registration of said first mentioned diagonal passage with said first mentioned radial casing passage. 10

Signed at Hammond this 7th day of August 1915.

ALBERT M. AUFTRING.
